UNITED STATES PATENT OFFICE.

JAMES E. BRIGGS, OF WATERLOO, IOWA, ASSIGNOR TO BRIGGS LABOR SAVING SPECIALTY COMPANY, OF WATERLOO, IOWA.

CONCRETE-SPREADER.

No. 896,616.

Specification of Letters Patent. Patented Aug. 18, 1908.

Application filed September 26, 1906, Serial No. 336,365. Renewed July 20, 1908. Serial No. 444,366.

To all whom it may concern:

Be it known that I, JAMES E. BRIGGS, a citizen of the United States of America, and a resident of Waterloo, Blackhawk county, Iowa, have invented certain new and useful Improvements in Concrete-Spreaders, of which the following is a specification.

My invention relates to concrete spreaders, and among its objects are, to provide a bottom-dumping-box for conveying concrete or other material to be used in street paving, and to provide such means for regulating and adjusting the movable bottom of said box as will permit its depositing the contained load 10 to any desired depth on the street. These objects I have accomplished by the means which are hereinafter described and claimed, and which are illustrated in the accompanying drawing forming a part of this specification, which shows in side elevation a four-wheeled spreader embodying the invention, and in dotted lines the dumping position of the device.

Referring to the numerals on the drawing, 25 23 indicates a containing box, that is suspended from a frame 22 mounted on wheels 24 in any usual or preferred manner. Said box may be of any proper size and shape, and is provided with a swing bottom 37, 30 hung so that the apparatus may discharge rearwardly, a hinge 38 thereon being swung from a transverse rod 39 mounted in hangers 40 attached to the sides of the box. In order to permit of the control of the device 35 from the driver's seat, the hand-lever 26 is fulcrumed in the upper end of a forward upright 25 of the frame, and is rotatable along a semi-circle 41 provided with a stop 42 to arrest its movement backward. A 40 link 28 has its forward end pivoted to the lever 26 on a stud 27, and its rear end pivoted to the upper end of a lever 30 on a stud 29. The lower end of said lever 30 is fulcrumed on a stud 35 extending from the side 45 of the box 23, as is also the lower end of a lever 34. 32 is a lever connecting the stud 33 of the upper end of the lever 34, and a stud 36 on the side of the swing-bottom 37. A chain 31 connects the upper ends of the 50 levers 30 and 32; and it will be observed that by the arrangement of parts shown, the levers 30 and 34 have the effect of a bell-crank construction when the hand-lever 26 is drawn forward to close the door 36, but 55 with the difference that the ends of the bell-

crank arms are movable toward each other and away from each other to a certain extent, the device operating as a bell-crank only when the ends of the arms are separated to the farthest extent permitted by the chain 31. Thus, when the bottom 37 moves over any obstruction, the slack of the chain 31 allows the bottom to move up and avoid breakage.

In practice, my improved spreader is used 65 in the following manner. When the load of freshly mixed concrete has been conveyed to the point of deposit, the swing bottom 37 may be dropped by simply carrying the lever 26 up and backward to the dotted line position of the drawing. The result is to allow the load on the swing bottom to take up the slack in chain 31, and to open downwardly. At the same time that the load is being dumped, the box is caused to move forward 70 until the load is entirely dumped. The moving forward of the box while the load is being discharged causes said load to be deposited in a layer of even thickness upon the ground, the thickness of said layer being determined 75 by the extent of opening of the bottom 37. Instead, therefore, of the load being deposited in an irregular or pyramidal heap, the greater part of which must be displaced and lowered to a common level by hard 80 manual labor, as will be the case with a load dumped in the usual manner, my improved spreader will itself grade the material being deposited, nothing more being needed than to trim up the edges of the layers at their 85 lines of juxtaposition. The saving of labor is obvious. This spreader, moreover effects the depositing of the concrete in a mass of more homogeneous character than usual. When the box has been filled with a load of 90 fresh material, the lighter portions thereof, or thin-cement binder, lies at the top over the lower stratum of mixed broken stone. A box dumped in the usual manner from the top will precipitate its upper stratum of liquid cement immediately upon the ground, the heavier broken stone following, and the concrete layer thus deposited lacks a sufficient amount of binding cement within its interstices. When my improved box is 95 dumped, from the bottom, the heavier stratum of broken stone is first deposited in a smooth layer upon the ground, while the upper stratum of liquid cement follows, is poured equally from the top on the 100 105 110

layer, penetrates uniformly the interstices thereof, and thus creates concrete of a uniform density and homogeneous consistency.

Having described my invention, what I claim as new, and desire to secure by Letters Patent, is—

1. A concrete-spreader, comprising a wheeled hopper provided with a transverse discharge-opening, a hinged door adapted to close the said opening, a hand-lever 26 pivotally connected to said hopper, a lever 30 pivoted on a stud 35 to said hopper, links connected between said levers 26 and 30, a lever 34 also on said stud 35, a lever 32 connected between the lever 34 and said hinged door, and a chain connecting the upper ends of said levers 30 and 32.

2. A concrete-spreader, comprising a

wheeled hopper provided with a transverse discharge opening in its bottom, a hinged door adapted to close said opening, a hand-lever pivotally connected to said hopper, a link pivotally connected to said hand-lever, a lever pivoted on said hinged door, and a bell-crank lever pivoted on the side of said hopper, the arms of said bell crank having a limited relative movability, and one arm being pivoted to said link and the other to the lever on the door.

Signed at Waterloo, Iowa, this 11th day of Aug., 1906.

JAMES E. BRIGGS.
